(57) **CLAIM**

The ornamental design for rotary dial, as shown and described.

DESCRIPTION

FIG. 1 is a top plan view of the rotary dial showing my new design;

FIG. 2 is a bottom plan view thereof;

FIG. 3 is a side elevational view thereof;

FIG. 4 is an opposite side elevational view of FIG. 3;

FIG. 5 is a side elevational view rotated ninety degrees from the rotary dial of FIG. 1, the opposite side is a mirror image;

FIG. 6 is a top plan view of a second embodiment of a rotary dial, the undisclosed bottom is not part of the claimed design;

FIG. 7 is a side elevational view thereof;

FIG. 8 is an opposite side elevational view of FIG. 7; and,

FIG. 9 is a side elevational view rotated ninety degrees from the rotary dial of FIG. 6.

The broken lines are for illustrative purposes only and form no part of the claimed design.
